N. E. LINSTROM.
AUTOMATIC STORM SASH ADJUSTER AND FASTENER.
APPLICATION FILED JAN. 2, 1920. RENEWED FEB. 6, 1922.

1,411,216.

Patented Mar. 28, 1922.

INVENTOR
Nils Edward Linstrom

UNITED STATES PATENT OFFICE.

NILS EDWARD LINSTROM, OF HAYTI, SOUTH DAKOTA.

AUTOMATIC STORM-SASH ADJUSTER AND FASTENER.

1,411,216.

Specification of Letters Patent. Patented Mar. 28, 1922.

Application filed January 2, 1920, Serial No. 348,921. Renewed February 6, 1922. Serial No. 534,825.

To all whom it may concern:

Be it known that I, NILS EDWARD LINSTROM, a citizen of the United States, residing at Hayti, in the county of Hamlin 5 and State of South Dakota, have invented a new and useful Automatic Storm-Sash Adjuster and Fastener, of which the following is a specification.

My invention relates to an original automatic storm sash adjuster and fastener, in 10 which an inclined rod bracket fastened to the storm sash operates in conjunction with a bracket fastened to either the upper or lower sash of the window proper.

15 The objects of my invention are: first, to provide an automatic opening and closing device for the storm sash; second, to provide an automatic adjustment of size of opening of storm sash in proportion to the 20 size of opening of the sash proper as it is raised or lowered; third, to provide an automatic fastener for the storm sash to hold the storm sash securely closed or at any 25 angle of opening; fourth, to provide for leverage and the reducing of friction in opening and closing the sash; fifth, to provide for convenience in attaching and detaching the storm sash.

I attain these objects by the mechanism 30 illustrated in the accompanying drawing, in which—

Figure I is a vertical view of the side 35 of the storm sash and the sash proper, showing all sash closed. Figure II is a vertical view of the side of the storm sash and the sash proper, showing the storm sash and the upper sash of the sash proper open. Figure I and Figure II show the mechanism used in conjunction with the upper 40 sash of the sash proper.

Figure III is a vertical view of the side 45 of the storm sash and the sash proper, showing all sash closed. Figure IV is a vertical view of the storm sash and the sash proper, showing the storm sash and the lower sash 50 of the sash proper open. Figure III and Figure IV show the mechanism used in conjunction with the lower sash of the sash proper.

55 Figure V is a detailed view of the bracket attached to the sash proper. Figure VI is a detailed view of the bracket attached to the storm sash.

Similar numerals refer to similar parts 55 throughout the several views.

Referring to the drawing the mechanism

consists of two brackets; bracket 4 is attached to storm sash 3 by means of screws. Bracket 5 is attached to sash proper 1 or 2 as desired. Bracket 5 is fitted with two grooved 60 anti-friction rollers 6 and 7 forming opening through which passes the rod arm or bracket 4. Bracket 5 is fitted with a removable pin 8, which holds in place roller 7. Upon removal of pin 8, bracket 4 may 65 be disengaged from bracket 5 and storm sash removed. Bracket 5 is provided with the anti-friction rollers 6 and 7 so that the sliding movement of bracket arm 4 may be accompanied with as little friction as 70 possible. When force is applied to upper sash 1 of the sash proper downwardly directed bracket 5 presses downward on inclined bracket 4, allowing sliding movement of the arm of bracket 4 and gradually forcing storm sash 3 outward. When force is applied upward on upper sash 1 of sash proper the reverse action takes 75 place, drawing storm sash 3 inward. The locking of upper sash 1 of sash proper automatically locks storm sash 3. My invention allows an opening of any angle or 80 size between positions of the sash shown in Figure I and Figure II and Figure III and Figure IV respectively.

85 The angle of bracket 4 may be increased or decreased according to leverage power desired.

The bracket 4 may be inverted at a lower 90 position on storm sash 3 and operated with bracket 5 also inverted and fastened at right angles on lower sash 2 of the sash proper as shown in Figure III and Figure IV. Operation of lower sash 2 of sash proper automatically operates storm sash 95 3 as hereinbefore indicated.

To secure rigidity and proper action, my invention provides for similar mechanism on both sides of window sash, thus requiring a similar mechanism on the opposite 100 side of window, although for convenience only one side of sash is herein described.

Storm sash 3 is attached to window frame 9 by means of hinge 10 which allows swinging movement of storm sash 3 as indicated.

105 While I have described and illustrated a certain use for my invention, I wish it to be understood that I do not wish to be limited to the use illustrated. Upon certain changes not affecting the principle of the 110 mechanism as described, it may be applied to various other uses.

I claim—

The combination, in a storm sash adjuster and fastener, of an inclined arm bracket fastened to the storm sash with a bracket 5 fitted with grooved anti-friction rollers and fastened to window sash proper, said first named bracket being slidably received between said rollers, whereby locking said sash proper locks said storm sash, and

opening or closing movement of said sash 10 proper imparts corresponding movement to said storm sash.

In testimony whereof I affix my signature in the presence of two witnesses.

NILS EDWARD LINSTROM.

Witnesses:

OLE JOHNSON,
H. A. LINSTROM.
